(57) **CLAIM**

The ornamental design for a machine for additive manufacturing, as shown and described.

DESCRIPTION

1. Machine for additive manufacturing

FIG. 1.1 is a right front perspective view of a machine for additive manufacturing, showing my design.

FIG. 1.2 is a left front perspective view of the machine for additive manufacturing.

FIG. 1.3 is a front view of the machine for additive manufacturing.

FIG. 1.4 is a back view of the machine for additive manufacturing.

FIG. 1.5 is a top view of the machine for additive manufacturing.

FIG. 1.6 is a left view of the machine for additive manufacturing.

FIG. 1.7 is a right view of the machine for additive manufacturing.

1 Claim, 7 Drawing Sheets
